UNITED STATES PATENT OFFICE.

LORENZO PLESCE, OF HAZLETON, PENNSYLVANIA.

SHADE AND CURTAIN SUPPORT.

Application filed April 24, 1926. Serial No. 104,412.

My present invention has to do with the support of window shades, curtains and the like; and it contemplates the provision of an efficient support adapted to be quickly 5 and easily applied to window frames of various widths and this without marring the frame, and in such manner that the brackets for carrying a shade or a curtain or both are strongly maintained against downward 10 movement without the imposition of undue strain on the elements by which connection of the brackets to the window frame is effected.

With the foregoing in mind, the invention 15 in all of its details will be fully understood from the following description and claim when the same read in connection with the drawings, accompanying and forming part of this specification:

20 Figure 1 is a front elevation showing the support of my invention as properly applied to a window frame.

Figure 2 is a side elevation of the same.

25 Figure 3 is a fragmentary top plan view showing one of the brackets, a portion of the window frame, and the means for effecting connection of the bracket to the frame.

Similar numerals of reference designate 30 corresponding parts in all of the views of the drawings.

The window frame or casing 1 may be of conventional construction or any other construction to which my improvement is suited, and by reference to Figure 1 it will be 35 noted that among other elements my improvement comprises two brackets 2. The said brackets 2 are identical in construction and therefore an explicit description of the bracket illustrated in Figures 2 and 3 will suffice to impart a definite understanding of both. It will be understood from Figures 2 and 3 that the bracket therein disclosed comprises a back or body plate 3, an inner arm 4 reaching forwardly from one end of said 45 back plate 3 and adapted to carry one end of a shade roller such as designated by 5 in Figure 2, and an outer arm reaching forwardly from the opposite end of the back plate 3, said outer arm being designated by 6 and being adapted to carry a curtain pole 7 and being of a greater length than the arm 4 in about the proportion illustrated in Figure 3. The said bracket, Figures 2 and 3, also comprises a loop 8 pendent from the 55 central portion of the back plate 3 and merged into a hook 9, the shank of the said

hook 9 being extended upwardly and rearwardly in inclined fashion from the loop 8 and being therefore, adapted to support a 60 rod section.

It will be apparent from the foregoing that each of the brackets comprised in my improvement is susceptible of being formed of a single piece of appropriate sheet metal, and I prefer in practice to so fabricate the 65 said brackets.

In addition to the brackets characterized as described, my improvement includes rod sections 10 with hooks 11 at their inner opposed ends, the said rod sections 10 being 70 designed to rest in and under the hooks 9 of the brackets 2, and on the hook shanks of said brackets so as to adequately support the brackets 2 when the backs of the plates 3 and the back portions of the pendent loops 8 are arranged against the face of the window frame 1 after the manner best shown in Figure 2. The hooks 11 of the two rod sections 10 are connected together 75 through the medium of a retractile spring 80 12, and the outer ends of the said rod sections 10 are shaped to form lateral arms 13 with barbs 14 at their extremities, the said barbs 14 being disposed longitudinally inward and being therefore, adapted to be 85 embedded in the side edges of the window casing 1 so as to support the rod sections 10 and therefore the brackets on the said rod sections 10 and the shade and the curtain carried by the said brackets. Any appropriate means may be employed to embed the barbs 14 and the rod sections 10 in the window frame or casing, and it will be noticed in this connection that the spring 90 12 will operate to prevent casual displacement of the barbs 14, and this notwithstanding the adaptability of the barbs 14 to be positioned at different distances apart so as to properly fit window frames or casings of various widths. It will also be apparent 95 that by virtue of the brackets 2 and the pendent loops 8 bearing solidly against the face of the window frame or casing 1, a considerable portion of the weight is taken off the barbs 14, this being due to the considerable bracket portions against the face of the frame 1 below the horizontal plane of the rod sections 10, and being also due in a 100 measure to the tendency of the brackets 2 to rock on the rod sections 10, whereby the pendent loops of the brackets as well as 105 the rear sides of the plates 3 will by the 110

weight of the shade and curtain be strongly pressed and held against the face of the frame 1.

It will be readily appreciated from the foregoing that my improvement while simple and inexpensive in construction is highly efficient in use and is well adapted as a whole to withstand the usage to which shade and curtain supports are ordinarily subjected; and it will also be appreciated that my improvement is susceptible of being readily accommodated to and expeditiously and easily applied on window frames or casings of various widths.

15 I have entered into a detailed description of the construction and relative arrangement of the parts embraced in the present and preferred embodiment of my invention in order to impart a full, clear and exact understanding of the said embodiment. I do not desire, however, to be understood as limiting myself to the precise construction and arrangement of parts disclosed, my invention being defined by my appended claim within

the scope of which modifications may be 25 made without departure from my invention.

Having described my invention, what I claim and desire to secure by Letters-Patent, is:—

The herein described support comprising 30 rod-like supporting means adapted to be secured in front of a face of a window frame or casing, and brackets each having a back plate adapted to bear against the face of a window frame or casing and forwardly extending 35 supporting arms on said back plate and each also having a portion integral with and pendent from the back plate in the same plane as said plate and a portion extending forwardly and upwardly and downwardly 40 from said pendent portion and adapted to rest back of and over the rod-like supporting means; the said pendent portion being adapted to cooperate with the back plate in preventing sagging of the forwardly extending 45 supporting arm on said back plate.

In testimony whereof I affix my signature.
LORENZO PLESCE.
